UNITED STATES PATENT OFFICE.

GEORGE H. DREW, OF BOSTON, MASSACHUSETTS.

DESIGN FOR AN ADVERTISING-COUPON.

SPECIFICATION forming part of Design No. 21,584, dated May 31, 1892.

Application filed April 20, 1892. Serial No. 429,953. Term of patent 14 years.

To all whom it may concern:

Be it known that I, GEORGE H. DREW, a citizen of the United States, and a resident of Boston, in the county of Suffolk and State 5 of Massachusetts, have invented and produced a new and original Design for an Advertising-Coupon, of which the following is a specification, reference being had to the accompanying drawing, in which the figure represents a plan or face view of a coupon having my design.

The leading feature of my design consists in a small single circle located slightly above the center of the coupon, a larger concentric 15 single circle having a diameter nearly equal to the width of the coupon, a series of single radial lines uniting the two circles, and a rectangular figure below the larger circle.

A is the central circle, within which is a 20 panel for any suitable letters or characters.

B is the larger circle, concentric with circle A and connected therewith by a series of single lines radiating from the inner to the outer circles. The larger circle is located on the coupon so as to closely approach three edges 25 thereof, and the space between the said circle and the fourth edge is occupied by a rectangular figure.

What I claim is—

The design for an advertising-coupon, substantially as shown.

In testimony whereof I have signed my name to this specification, in the presence of two subscribing witnesses, this 18th day of April, A. D. 1892.

GEORGE H. DREW.
